UNITED STATES PATENT OFFICE

115,531

DESIGN FOR A WATER JUG OR SIMILAR ARTICLE

Walter T. Stopa, Chicago, Ill., assignor to Edison General Electric Appliance Company, a corporation of New York

Application December 14, 1938, Serial No. 81,783

Term of patent 14 years

To all whom it may concern:

Be it known that I, Walter T. Stopa, a citizen of the United States, residing at Chicago, in the county of Cook, State of Illinois, have invented a new, original, and ornamental Design for a Water Jug or Similar Article, of which the following is a specification, reference being had to the accompanying drawing forming a part thereof.

Fig. 1 is a perspective view of a water jug or similar article showing my new design, and Fig. 2 is a perspective view of the water jug shown in Fig. 1 taken from a point of view diagonally opposite to that of Fig. 1.

I claim:

The ornamental design for a water jug or similar article, as shown.

WALTER T. STOPA.
